US00D883472S

(12) **United States Design Patent** (10) Patent No.: **US D883,472 S**
(45) Date of Patent: ** May 5, 2020

(54) **CONTROL PANEL WITH DISPLAY FOR FEEDING DEVICES**

- (71) Applicant: **N.V. Nutricia**, Zoetermeer (NL)
- (72) Inventors: **Mark Hogerwerf**, Utrecht (NL); **Sencha Van Kinderen**, Utrecht (NL); **Arie Abraham Zuijderduin**, Utrecht (NL); **William Bartrip**, Schiphol Airport (NL); **Christiaan Gerardus Johannes Weel**, The Hague (NL); **Fedor Christiaan Kadiks**, Haarlem (NL)
- (73) Assignee: **N.V. Nutricia** (NL)
- (**) Term: **15 Years**
- (21) Appl. No.: **29/636,454**
- (22) Filed: **Feb. 8, 2018**

(30) **Foreign Application Priority Data**

- Dec. 6, 2017 (EM) 004537694-0001
- (51) **LOC (12) Cl.** **24-02**
- (52) **U.S. Cl.**
USPC **D24/111**

CLAIM

The ornamental design for a control panel with display for feeding devices, as shown and described.

DESCRIPTION

FIG. 1 is a front perspective view of a control panel with display for feeding devices according to our invention; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; and, FIG. 7 is a bottom plan view thereof.

The broken lines in FIG. 4 depict parts of the control panel with display for feeding devices that form no part of the claim.

1 Claim, 3 Drawing Sheets
